CORPORATION OF WEST VIRGINIA.

MOTOR-TRUCK.

1,069,991.

Specification of Letters Patent. Patented Aug. 12, 1913.

Application filed July 22, 1912. Serial No. 710,890.

To all whom it may concern:

Be it known that we, CHARLES E. F. AHLM and CLYDE E. COCHRAN, citizens of the United States, and both residing at Cleveland, in the county of Cuyahoga and State of Ohio, have invented a certain new and useful Improvement in Motor-Trucks, of which the following is a full, clear, and exact description, reference being had to the accompanying drawings.

The object of this invention is to provide a motor truck with effective and automatically operating controlling means. We accomplish this by connecting the brake and a controlling device with movable platforms on which the operator may stand and which are caused automatically to rise when relieved of weight. Thus the brake is automatically applied when the operator removes his weight from one of the platforms, and the controller is automatically disconnected when his weight is removed from the other platform.

A further object of our invention is to adapt such controlling system to a double ended motor truck; that is, a truck adapted to run forward in either direction, as, for example, a baggage truck.

Our invention is well adapted for embodiment in an electric motor truck, though not confined thereto.

Our invention includes the platform control of the vehicle and also the double ended embodiment, as hereinafter more fully explained and definitely set out in the claims.

In the drawings, Figure 1 is a sectional plan of a truck embodying our invention; Figs. 2 and 3 are vertical longitudinal sections of the same, as indicated by the lines 2-2 and 3-3 on Fig. 1; Figs. 4 to 7 inclusive are perspective views of various rocking members which engage the platforms and are controlled thereby; Fig. 8 is a front elevation of the truck; Fig. 9 is a detail in section across adjacent platforms, as indicated by the line 9-9 in Fig. 1; Fig. 10 is a detail, in vertical section, through the controller-centering spring.

The truck shown in the drawing is an electric truck of the drop frame type shown and claimed in Patent No. 993,823, granted May 30, 1911, to Tracy V. Buckwalter. Such drop frame has a bottom portion or beams 10, and housings 11 and 12 near the ends in

which are mounted the wheels 13, axle frames, driving and controlling mechanism, brakes, batteries, etc. The wheels are shown in Fig. 8 as connected with axles from the axle frame 15 and as having internal gears 16 which mesh with driving pinions 17, by which the machine is driven. The pinions are on the ends of driving shafts which are contained within a suitable housing 18 and are driven by a suitable motor, not shown. It is to be understood that the construction so far described is chosen as illustrative, but may be varied, as may be desired.

Suitably secured to the frame, near one end, is the controller 20. The controller 70 may be of the type shown, described and claimed in the application of Clyde E. Cochran (one of the present inventors) filed concurrently herewith; or, it may be of other type, as desired. The controller is 75 suitably carried by the frame, as by the suspending brackets 28 and 29, Fig. 8, and is provided with an operating shaft 21. Connecting with this shaft is a rock arm 22, from which a link 23 leads to an intermediate pivoted controlling lever or handle 24. By this means the handle may rock the shaft and control the vehicle from that end.

To control the vehicle from the other end, I mount on the other end of the shaft 21 a 85 rock arm 25, which is shown as connected by a suitable system of links and levers with the controller handle 27 on the other end of the vehicle. Such system of links and levers, includes the link 30, rocking 90 member 31, link 32, lever 33, link 34, lever 35, link 36, bell crank 37, and link 38, the latter connecting with the controller lever 27, which is shown as pivoted at 39. For convenience of illustration, we have shown 95 two controlling handles 24 and 27, but it is to be understood that, in practice, a single interchangeable handle will be employed, and such removable handle may enter sockets, as illustrated in Fig. 3, or be otherwise 100 connected with the controlling linkage.

The controller is designed to have a mid-position of rest, or "off" position, and when the barrel is turned in one direction therefrom the current is connected to propel the 105 vehicle forwardly, while, when the barrel is turned in the opposite direction the vehicle is propelled rearwardly. To give the con-

troller shaft a tendency to automatically return to "off" position, I provide a spring 40 which acts on a rod 41 connected with the arm 22 and tends to return that arm to its mid-position. This is easily accomplished by mounting the spring in a yoke 42, which is pivotally connected at 43 with the truck frame, the rod having a shoulder adapted to push downwardly on a washer 10 which engages the upper end of the spring and presses it downwardly when the rod is moved downwardly, and having also a shoulder adapted to push upwardly on a washer 45 which engages the lower end of 15 the spring and presses it upwardly when the rod is moved upwardly.

From the above description, it will be understood that we have a controller with contact plate and fingers so arranged that, 20 when the barrel is turned in one direction from the "off" position, the vehicle is driven ahead, and when turned in the opposite direction the vehicle is driven rearwardly. The system of links and levers connecting 25 the two handles 24 and 27 which control the barrel are so arranged that when the lever 24 is elevated, the handle 27 is depressed, and vice versa. Now, assuming that an elevation of the handle is to give forward direction to the movement, such result follows 30 at each end of the vehicle, because of course forward movement for one end is the reverse for the other. So, depressing the handle at each end would be reversing the controller and driving the vehicle backward with reference to that end.

The controller being effectively operated by raising or lowering the lever at either end of the vehicle by an attendant standing on a 40 suitable platform, we have found it very convenient to arrange the brake to be applied according to the attendant's position or weight on the platform. To this end we supply, at each end of the vehicle, two platforms side by side, one of which controls the brake. When the operator stands with 45 one foot on each platform, the vehicle is in running order, but when his weight is shifted from the brake-controlling platform, the 50 brake is automatically applied. We will now describe this brake applying mechanism.

Any suitable form of brake is used. As shown in Fig. 2, there are a pair of brake shoes 50 and 51 pivoted together at 52 and 55 adapted to be forced apart within the brake drum 54, which is rotatable with the driving mechanism. Such forcing apart of the shoes is accomplished by rocking a block 56, which is connected with a rock arm 57, which is connected by the link 58 with a bell crank 59, from which a link 60 leads to a rock arm 61, which is sleeved on the transverse shaft 67, on which the platforms at that end are hinged. The brake-applying platform at this end is designated 65 and

the sleeve 62 has an arm 63 extending beneath this platform. A spring 64 acting at a suitable point, tends to rock the arm 57 in the direction to apply the brake, while the platform 65, when down, by reason of its holding down the rock arm 63, prevents the application of the brake. Now, whenever the weight is removed from the platform 65 the spring 64 is allowed to act, and this raises the arm 57 and applies the brake. 70

We have referred in the above paragraph to the left hand end of the vehicle as shown in the drawings, but the brake is applied in the same direction by raising the platform 66 at the right hand end. This is accomplished by a link 70 (adjustable by means of a turn buckle 71) which connects the bell crank 59 with a rocking arm 73 and with a link 74, which connects with a rock arm 75 on a sleeve 76, which is on the rod or shaft 85 77 of the platform 66 and has a rock arm 78 lying beneath that platform. From this it results that, whenever the platforms 65 and 66 are raising to release the rock arms 63 or 78, the brake is applied by the spring 90 64. When, however, either platform is down, the brake is held out of action thereby. Accordingly, in running, the operator simply controls the braking by raising his foot from the platform 65 or 66; that is raising the right foot in each case, assuming that the operator stands with his back to the vehicle, facing forwardly. This system of control is extremely simple and leaves the operator's right hand free for steering. Furthermore, should the operator leave the vehicle, the brake would be automatically applied by the raising of the platforms 65 or 66. As the controller automatically goes to "off" position, this would effectively stop 100 the vehicle. 105

To insure against accident in case the operator should leave the vehicle and the controller thereafter be turned on by some unauthorized person, or, in case the controller handle should become jammed against something and not go to "off" position automatically, we provide an automatically opened switch in the controller circuit, operated by the raising of that platform on which the operator's left leg normally bears. 110

In accomplishing the desired result, we connect the supplemental switch (not shown, but which may be of any suitable form) in the controller casing with a link 120 80, so that, when the link is raised, the switch is open. This link is connected at its lower end with a bell crank 81, with which connects a link 82, the other end of which is connected with a rock arm 83 on a sleeve 84 having an arm 88 extending beneath the platform 85. The bell crank 81 is also connected with a rod 90, adjustable by the turn buckle 91 and connected at its other end with the rocking arm 92 and the 125 130

link 93, which connects with a rock arm 94, on the sleeve 95, which has an arm 96 extending beneath the platform 86. A suitable spring 98 is mounted on the rod, and being compressed between a head 99 thereon and a stationary frame bracket 100, tends to shove the rod 90 toward the left, (in Fig. 3), which is the direction to raise the rod 80 and open the supplemental contact. This opening will accordingly result whenever the two platforms 85 and 86 are raised. When, however, either platform is down, the system of links shown is held in the position appearing in Fig. 3 and the supplemental contact is thus closed.

Simple and effective forms of the various rocking members, to enable the systems of links and the platforms to coöperate as explained, are shown in Figs. 4 to 7 inclusive. Fig. 4 represents the rocking member mounted on the shaft 67 and connecting the platform 65 with the brake system of linkage. Fig. 5 shows the rocking member mounted on the rod 77 which connects the controller system with the platform 86. Fig. 6 shows the rocking member mounted on the shaft 67 and connecting the controller system with the platform 85; and Fig. 7 shows the rocking member mounted on the shaft 77 and connecting the brake system with the platform 66. By means for these rocking devices, we are able to conveniently connect the brake rod and the controller rod, both of which are shown as mounted on the same side of the truck frame with the two platforms, right and left, at the two ends of the vehicle.

We provide the two brake platforms 65 and 66 with laterally projecting lips 69 which overhang corresponding lips 68, projecting from the platform 85 or 86, so that, whenever the brake platform is held down, the controller platform is automatically held down thereby, and there is no possibility of the controller platform rising to shut off the power when the attendant is standing on the brake platform. This enables the attendant to stand entirely on the brake platform, which is on the side where the steering lever is, should conditions make it desirable to do so.

In order that the holding down of the platform at either end of the vehicle shall automatically hold up the platform at the opposite end, we provide a chain 104 connecting the platforms 65 and 86 and passing over suitable pulleys 105, and a chain 106 passing across pulleys 107 and connecting the platforms 85 and 66. When the platforms at both ends of the vehicle are uncoupled, the springs 64 and 98 shove the platforms 65 and 85 upwardly into a diagonal position, and thereupon the platforms 66 and 86, having their chains slackened, drop by gravity into a corresponding position.

In this position, the brake is applied, and the supplemental switch of the controller is in the open position. Now when the attendant steps on the platforms at one end, these go down by his weight and the corresponding platforms, at the other end, are raised into a more nearly inaccessible position by means of the chains. If the attendant steps on both platforms at one end, or on the brake applying platform alone, such movement releases the brake and also closes the supplemental controller contact so that the vehicle is in position for running. However, if he steps only on the controller platform, he closes the supplemental contact, but leaves the brake applied. Then he is in a position to release the brake to as great or little extent as desired, by raising the right foot, and to properly direct the current by operating the controller handle.

Our system of platform control is admirably adapted for baggage trucks adapted to run on station platforms where it is important to be able to accurately and quickly control the truck, and moreover, where means must be provided to prevent tampering or accident, because the attendant frequently leaves the platforms to assist in loading or unloading the baggage. Our trucks, moreover, are adapted to be operated by an ordinary baggage man not having special skill in handling motor vehicles.

Having thus described our invention, what we claim is:

1. In a vehicle, the combination of a brake, mechanism adapted to hold the brake in idle position and including a rock arm, a pivoted platform adapted to rest on said rock arm or be free therefrom, whereby the platform may be turned to idle position without unduly rocking the shaft, and a spring acting on the mechanism and adapted to apply the brake when the platform releases the arm.

2. The combination, in a vehicle, of a brake, platforms at the opposite ends of the vehicle, mechanism connecting the brake with the two platforms, and means for connecting the two platforms together so that the depression of one platform raises the other.

3. In a vehicle, the combination of a brake, means tending to apply it, mechanism to hold the brake out of application, and a movable platform at each end of the vehicle adapted when depressed to act on said mechanism to hold the brake in idle position, and a connection between said platforms adapted to raise one when the other is depressed.

4. In a vehicle, the combination of a brake, a spring for applying it, mechanism to hold the brake out of application, and a hinged platform at each end of the vehicle adapted when depressed to act on said mech-

- anism to hold the brake in idle position with the spring constrained and tending both to raise the platform and apply the brake, and a connection between said platforms raising one when the other is depressed. 5
5. In a double ended motor truck, the combination, with the frame, of a platform hinged at each end of the truck, connecting chains between the two platforms whereby 10 when either platform is folded down the other is thereby elevated, a brake, connecting mechanism between the same and the two platforms, whereby the depression of either platform holds the brake out of action, and a spring tending to apply the brake when released by the platform. 15
6. In a double ended motor truck, the combination, with the frame, of a platform hinged at each end of the truck, connecting mechanism between the two platforms whereby 20 when either platform is folded down the other is thereby elevated, a brake, connecting mechanism between the same and the two platforms, whereby the depression of either 25 platform holds the brake out of action, a spring tending to apply the brake when released by the platform, a controller and two operating means therefor located respectively at the opposite ends of the vehicle and accessible to an attendant standing on the corresponding platform. 30
7. In a motor vehicle, the combination, with the wheels and frame and driving mechanism, of a brake, a controller and two platforms, means tending to raise said platforms, mechanism connected with one platform for applying the brake when the platform rises, and mechanism connected with the other platform for controlling the controller. 35
- 40 8. In an electric motor truck, the combination, with the wheels and frame and driving mechanism, of a brake, a controller, two platforms side by side at the end of the truck adapted to support a standing attendant, means tending to raise said platforms, mechanism connected with one platform for applying the brake when the platform rises, and mechanism connected with the other platform for controlling the circuit when the platform rises. 45
- 50 9. The combination, in a motor vehicle, of a controller, a brake, a pair of platforms side by side, mechanism tending to apply the brake and adapted to be held in idle position by the depression of one of the platforms, and mechanism tending to open the controller circuit and adapted to be held in idle position by the depression of one of the 55 platforms, and mechanism tending to open the controller circuit and adapted to be held in idle position by the depression of the other platform. 60
- 65 10. In a motor vehicle, the combination, with the wheels and driving mechanism, of a 70
- a brake and a controller, a pair of platforms side by side at the end of the vehicle, mechanism tending to apply the brake, connections between said mechanism and one of the platforms, whereby when the weight is taken off of the platform the brake is applied, a supplemental switch and connecting mechanism between it and the other platform whereby the switch is opened when that platform is allowed to rise. 75
11. The combination, in a motor vehicle, of a controller, a brake, a pair of platforms side by side and either adapted to support the weight of an attendant, a connection between one platform and the brake, a connection between the other and the controller, a connection between the two platforms making one dependent on the other while leaving the latter free from the former, and means tending to raise the two platforms. 80
- 85 12. The combination, in a motor vehicle, of a controller, a brake, a pair of platforms side by side, mechanism tending to apply the brake and adapted to be held in idle position by the depression of one of the platforms, mechanism tending to open the controller circuit and adapted to be held in idle position by the depression of the other platform, and a connection between the two platforms enabling the brake applying platform to rise without the raising of the circuit-controlling platform but compelling the brake applying platform to rise when the circuit-controlling platform rises. 90
- 95 13. In an electric motor vehicle, the combination, with an electric controller for the driving mechanism and a brake therefor, of a pair of platforms side by side at the forward end of the vehicle and adapted to support the weight of the attendant, a controller lever accessible to the attendant while on the platform, mechanism for applying the brake, a spring tending to actuate said mechanism, mechanism for holding the brake out of action and adapted to engage and coact with one of the platforms, a switch in the controller circuit, mechanism connecting it with the other platform, and a spring tending to actuate it when the other platform is raised, whereby the raising of one platform applies the brake and the raising of both platforms applies both the brake and opens the switch. 100
- 105 14. In a motor truck, the combination, with a frame, of movable platforms at each end of the truck, a controller, manual mechanism from each end of the truck connected with the controller for operating the same, an automatic switch for opening the controller connected with a platform at each end and adapted to be closed when either of such platforms is depressed, and means operating by the other platform at each end for applying the brake. 110
- 115 15. In a motor truck, the combination, 120

with a frame, of movable platforms at each end of the truck, a controller, manual mechanism at each end of the truck connected with the controller for operating the same, 5 an automatic switch for opening the controller connected with a platform at each end and adapted to be closed when either of such platforms is depressed, means operated by the other platform at each end for applying the brake, and means connecting the 10 brake platform at each end with the controller platform at the other, whereby when the platforms at one end are depressed those at the other end are elevated.

15 16. In a vehicle, the combination, with a brake adjacent to one end of the vehicle, a platform at that end, a platform at the opposite end, mechanism for applying the 20 brake, connections between such mechanism and each of the platforms, whereby either platform when depressed may hold the brakes in idle position, and a support for the operator adjacent to each platform.

25 17. In a vehicle, the combination, with a brake adjacent to one end of the vehicle, a platform at that end, a platform at the opposite end, mechanism for applying the 30 brake, connections between such mechanism and each of the platforms, whereby either platform when depressed may hold the brakes in idle position, and an additional platform at each end of the vehicle adjacent to the platform first mentioned, a controller 35 adjacent to one end of the vehicle, connecting mechanism between the same and each additional platform, whereby the raising of the first-mentioned platform may apply the brake and the raising of the additional platform may effect the control.

40 18. The combination, of a motor vehicle, a brake and a controller thereon, a pair of platforms side by side at the end of the vehicle hinged on a cross rod, a spring tending to 45 apply the brake, a spring tending to open a switch on the controller, mechanism for holding the switch closed and the brake applied in opposition to said springs, said mechanism including rocking members on the said cross rod having arms engaging the under sides of the respective 50 platforms.

55 19. The combination, of a motor vehicle, a 60 brake and a controller thereon, a pair of

platforms side by side at the end of the vehicle hinged on a cross rod, mechanism for holding the controller idle and the brake applied, said mechanism including rocking members on the said cross rod having arms engaging the under sides of the respective platforms, and a lip on the brake applying platform overlapping the controller platform.

20. The combination of a motor vehicle, a brake and a controller thereon, a pair of movable platforms side by side at one end of the vehicle, a spring tending to apply the 65 brake, a spring tending to open a switch on the controller, mechanism for holding the switch closed and the brake applied in opposition to said springs, said mechanism including rocking members having arms engaging the under sides of the respective platforms, corresponding movable platforms at the opposite end of the vehicle, and mechanism connecting the same with the brake and the switch mechanisms.

25 21. The combination in an electric truck, of a running frame, a brake and a controller thereon, a pair of platforms side by side at one end of the truck, hinged on a cross rod, a spring tending to apply the brake, a spring 80 tending to open a switch on the controller, mechanism for holding the switch closed and the brake applied in opposition to said springs, said mechanism including rocking members on the said cross rod having arms 85 engaging the under side of the respective platforms, correspondingly hinged platforms at the opposite end of the truck, links extending through the base of the truck and connecting such platforms with the 90 brake and switch mechanisms, mechanism connecting the platforms at one end of the truck with those at the other end, and means accessible at each end of the truck for operating the controller.

95 In testimony whereof, we hereunto affix our signatures in the presence of two witnesses.
